Application December 23, 1940, Serial No. 371,358

23 Claims. (Cl. 178—4.1)

The present invention relates generally to telegraph transmitters and receivers and more particularly to telegraph transmitters and receivers adapted to facsimile telegraph systems.

In telegraph systems involving apparatus for recording characters by a series of elemental areas of positive and negative surfaces, each letter symbol or character is scanned or analyzed into a succession of constituent areas, and a transmitting element representative of each letter symbol or character is constructed in accordance with such analysis. Electrical impulses accordingly are generated to control and to operate a receiving printer of the type generally disclosed in Patent No. 2,131,741, granted October 4, 1938, to E. E. Kleinschmidt et al., to form the characters line by line.

An object of the invention is the provision of a transmitter operative from a control strip to assure the operation of its associated receiver prior to transmission of signal impulses representative of characters, letters, or symbols.

Another object of the invention is the provision of a transmitter operative under control of a control tape equipped to preclude advancement of the tape until the lapse of a predetermined time interval.

A feature of the invention resides in the provision in a transmitter, arranged with a plurality of transmitting elements, one for each character, letter, or symbol, which are rendered effective by a control tape, of electrical contacts operated in succession for establishing receiver motor control conditions and tape control conditions to condition the receiver for operation and to start the tape for control of the transmitting elements.

The above and other objects of the invention are achieved through the provision of a mechanism for sensing perforations in a tape perforated in accordance with a five-unit or Baudot code which, through its electrical contacts, controls the energization of a plurality of electromagnets, one individual to each element of the permutation code. These electromagnets serve to control the selective position of permutation bars, which accordingly will be set in varying combinations in accordance with the code combinations of perforations appearing in the perforated tape. The permutation bars for each permuted setting serve to select a pair of brushes. Individual to each pair of the brushes is a pair of code discs designed in accordance with a method of prescanning in which the characters or symbols to be transmitted are divided into any desirable number of sending units or areas. The several unit areas thus

created are assigned in the order of scanning to the periphery of a code disc.

Specifically, the two discs constituting a pair of code discs are allocated to letters and figures, or lower and upper case characters, respectively. With the selection and cooperation of a pair of brushes with a pair of code discs it is necessary to select between the pair of code discs. To accomplish such a result, mechanism is responsive to shift and unshift signals appearing in the perforated tape to select between a pair of collector rings, one identified with the shift signal and the other identified with the unshift signal. Under such circumstances one disc of each of the pairs of discs will be connected to one of the collector rings; whereas the other disc of each of the pairs of discs will be connected to another collector ring, and by selecting between the collector rings in accordance with the shift and unshift signal combinations, the impulses indicative of the character to be transmitted can be selectively determined.

The code discs are rotated continuously by power communicated thereto from a continuously rotating motor, and since the brushes are selectively operated in accordance with the permuted setting of the permutation bars, impulses representative of the positive and negative surfaces of the character will be transmitted. These impulses will be effective at the receiving station to record a character in accordance with the pattern of the character formed on the periphery of the code disc then effective for the transmission of the characteristic impulses.

The code discs rotate continuously, and the permutation bars are set permutable in response to the energization of electromagnets, as previously outlined. Energization of the electromagnets is under the control of a tape sensing mechanism which receives its operating impulse from a cam operated in timed relation with the rotation of the code discs. For each rotation of the discs and the indicated cam, an impulse is generated to effect the energization of an electromagnet of the tape sensing mechanism to withdraw its tape sensing fingers and advance the tape to present the next transverse row of perforations in alignment with the tape sensing elements of the sensing mechanism. Under predetermined conditions it is desired to arrest the operation of the transmitter or the tape sensing mechanism, and therefore mechanism under the control of the condition of the perforated tape is provided whereby the impulse generated cyclically through the operation of the cam will not be effective to

energize the electromagnet of the tape sensing mechanism to withdraw the sensing fingers from cooperation with the tape and advance the tape.

In accordance with established practice the tape is prepared by either a keyboard perforator or a signal controlled perforator, and regardless of the manner in which the tape is prepared, a section of tape intervenes between the perforator and the tape sensing mechanism. Dependent upon the condition of this intervening section of tape the impulse generated by the cam, which may be identified as the pulsing cam, is effective or ineffective.

Depending upon whether the tape between the perforator and the sensing mechanism is slack or taut, an electromagnet will be controlled for determining the position of an arm which is adapted to engage the threads of a continuously rotating screw; first, to engage and close contacts for establishing a condition to control the starting of the operating motor of the receiving printer at the receiving station, and secondly, to close contacts to render the impulse generated by the pulsing cam effective to permit operation of the tape sensing mechanism through the advancement of the tape to present the next transverse row of perforations in alignment with the sensing fingers and permit transmission of impulses in accordance with such transverse row of perforations. Such a condition prevails as long as the tape intermediate the perforator and the sensing mechanism does not become taut.

At the receiving station the receiving printer, which may be of the general form and construction disclosed and described in Patent No. 2,000,083 to E. F. Kleinschmidt of May 7, 1935, has the circuit of its driving motor normally open; consequently, it is desirable, upon the receipt of the first effective impulse from the transmitter, to establish a condition at the receiving printer whereby the circuit of its driving motor will be closed and it will attain its desirable operating speed. Specifically, the receiving printer is arranged with mechanism whereby upon a predetermined cessation of signal impulses the operating circuit of its driving motor will be opened automatically, and its motor will be stopped pending the receipt of an impulse which establishes a condition whereby the operating circuit of the motor is again closed.

The invention will be explained hereinafter more fully with reference to the accompanying drawings, of which

Fig. 1 shows in perspective, elements of the transmitter adaptable for the achievement of the objects of the present invention;

Fig. 2 is a view of certain elements of the transmitter operatively arranged with the tape sensing mechanism and the controls for generating impulses to condition the tape sensing mechanism for operation and for starting the motor of the receiving printer located at the remote station, which may be interconnected with the transmitting station either through a radio channel or a wire channel;

Fig. 3 shows diagrammatically the arrangement of the contacts for generating the control impulses and the path of operation of the mechanism for effecting such operation;

Fig. 4 shows the receiving printer; and

Fig. 5 shows schematically a modified form of the transmitter and the sensing mechanism disclosed in Fig. 2.

Referring now to the drawings, particularly to Fig. 1, it is noted that shaft 9 has secured thereto

a pinion gear 10 which meshes with a worm gear 11 driven by power communicated from a continuously rotating motor 12 (Fig. 3). The relation between gears 10 and 11 is such as to cause rotation of shaft 9 at a speed calculated to effect the accurate and proper distribution of current impulses indicative of the characters to be transmitted. Secured also to shaft 9 are a plurality of code discs 13. These code discs, as best shown in the lower part of Fig. 2, are composed of a plurality of discs arranged in pairs; that is, a pair of code discs 13 constitute a unit, one disc of which corresponds to a lower case character, whereas the other disc corresponds to an upper case character.

Code discs 13 are designed according to a method of prescanning in which characters or symbols to be transmitted are divided into any desirable number of sending units or areas. The several unit areas thus created are assigned in order of scanning to the periphery of each of the discs 13, the dark areas of a signal or message unit being the high surfaces 14 to engage a brush designed to cooperate therewith to send signal impulses. It is, of course, obvious that the depressed or reduced portions of the code discs 13 represent the light areas of the signal or message unit. Obviously, the light areas might be made the high surfaces, depending upon the preferred method of transmission and of reproduction.

The term "mechanical prescanning" refers to the analysis of a character in the signals suitable for transmission and comparable to the scanning of the character. The production of the mechanical member or disc containing elements thereby corresponds directly and individually to the signals and represents individual characters. For example, a character or letter may be prescanned by dividing its total area into a plurality of unit areas arranged in a predetermined number of vertical strips with a predetermined number of units within each strip. The character is thus divided into a plurality of strips laid out in a predetermined number of equal angular sectors on the discs 13, and each angular sector is divided into a predetermined number of angular units, each corresponding to a unit area of the corresponding vertical strip. The periphery of the code disc 13 is then laid out by recessing the corresponding disc unit sections of each sector whereby the respective unit areas are light, and where the units are dark, raised surfaces 14 are provided. With such a plan each of the code discs 13 is correspondingly developed.

From the foregoing explanation of the arrangement of the code discs 13, it is evident that the present invention contemplates a code disc for each character or symbol to be transmitted; that is, there will be a code disc 13 individual to each letter of the alphabet and each numeral or other special characters. These code discs, being secured to, but insulated from, shaft 9, will rotate therewith continuously, and during their rotation, provided a selection has been established, will effect the transmission of signal impulses indicative of their allocated character.

The discs 13 are arranged in pairs, and being so arranged, it is necessary to interconnect a disc of each pair which, in turn, are connected to a collector ring 15 which is also secured to shaft 9. Likewise, the other code disc of each of the pairs of code discs are interconnected and, in turn, are connected to a collector ring 16 which, as noted for collector ring 15, is also secured to shaft 9. Interconnection of the several code discs with the

collector rings 15 and 16, respectively, is achieved through the provision of conductor rods 17 and 18. These rods 17 and 18 are parallel to shaft 9 and extend through the code discs 13 and are connected to alternate code discs of each pair of code discs. Rods 17 and 18 are as shown in Fig. 2 connected to collector rings 15 and 16, respectively.

In addition to code disc 13 and collector rings 15 and 16 there are secured to shaft 9 other discs which serve, through their cooperation with brushes individual thereto, to transmit a start signal at the beginning of each resumption of message transmission, as will be explained hereinafter.

In the operation of the transmitter constituting the present invention certain functional operations are required. Such functional operations are performed by cams 24, 25, 26, and 27 secured to shaft 9. These cams are positioned on shaft 9 with respect to each other and with respect to code discs 13 to perform their respective functions in timed relation with the other functional responses and the transmission of signal impulses as determined through the rotation of code discs 13. It is obvious, therefore, that the cams 24, 25, 26, and 27 may be oriented on shaft 9 with respect to each other to provide proper sequential operation in a manner fully contemplated by the present invention.

Positioned with respect to shaft 9 and the code discs 13 are a plurality of permutation bars 31, 32, 33, 34, and 35, one individual to each element of the code. According to the embodiment of the invention disclosed in the aforementioned drawings, a five-unit code is employed, and therefore there are five permutation bars or one individual to each element or unit of the code. Operation of the permutation bars is attained through the arrangement of an electromagnet individual to each of the bars. Under such circumstances there are five electromagnets 37, 38, 39, 40, and 41. These electromagnets are selectively controlled from a tape sensing mechanism 43 and control, through their armature, a spring-held latch 44 which engages a shoulder formed on the upper edge of its permutation bar to hold it against the action of its individual spring (not shown). Under such circumstances, when an electromagnet is energized the spring restored latch 44 is operated to move its end free of the projection on the upper edge of its permutation bar, whereupon such permutation bar is moved to the left, as viewed in Fig. 2, by the action of its individual spring (not shown).

The tape sensing mechanism 43, as is fully and completely disclosed in Patent No. 1,460,357 to E. E. Kleinschmidt of June 26, 1923, embodies a plurality of tape sensing fingers 47 which serve to sense perforations in tape 48, which has been perforated through the operation of a keyboard perforator or a signal controlled reperforator to form transverse rows of code perforations indicative of the characters or symbols of the message to be transmitted through the effectiveness of code discs 13. As is fully disclosed in the aforementioned Kleinschmidt Patent No. 1,460,357, the sensing fingers 47 are pivoted on a rod 49 and are movable about such rod by an electromagnet 50. Specifically, electromagnet 50, upon being energized, draws its magnetic yoke 51 to shift its cores axially to push a non-magnetic pivoted bail plate 52 against the five tape sensing fingers 47 and thus withdraw the sensing fingers 47 from engagement with the perforations in tape 48 and

causes, following such withdrawal, the advancement of the tape through a ratchet and pawl mechanism (not shown) to present the next transverse row of perforations in alignment with the projecting ends of the sensing fingers 47. The magnet core of electromagnet 50 is, of course, so designed as to respond in well-known manner to the energization of said magnet, and said core is provided with non-magnetic extensions which engage the bail 52.

Attached to and operated by each of the sensing fingers 47 is a contact spring 54. There being five sensing fingers 47, there are five contact springs 54 which cooperate with stationary contacts 55 to effect a circuit closure and cause, through the instrumentality of a battery, the energization of the electromagnet connected thereto; namely, to cause the energization of the respective electromagnets 37-41.

Assume, for example, that a sensing finger 47 encounters a perforation in tape 48. Through its contact spring 54 an energizing circuit for the electromagnets 37-41 connected thereto will be established. The electromagnet will be energized and latch 44 will be operated against the action of its spring to free the permutation bar individual thereto for action by its spring (not shown). Such permutation bar will be moved to the left, as viewed in Fig. 2.

Under certain conditions of operation it is desirable to prevent the operation of the tape sensing fingers 47, notwithstanding the fact that the electromagnet 50 may be energized cyclically. In order to achieve such a result, an electromagnet 57 having an armature 58 is provided. Through bail plate 52 electromagnet 57 locks the armature of electromagnet 50, so that notwithstanding the fact that the electromagnet 50 is energized cyclically, it will have no functional response on the sensing fingers 47, its cores merely engaging bail plate 52, which is attached rigidly to the armature 58 of electromagnet 57.

As shown in Figs. 1 and 2, the lower edge of each of the permutation bars 31-35 is formed with a plurality of notches arranged permutably so that upon the permuted operation of electromagnets 37-41, corresponding operation of permutation bars 31-35 will result in the alignment of the notches to effect the selection of one of a plurality of selectable bars 61. There is a selectable or selecting bar 61 individual to each pair of code discs 13. Each selectable bar 61 is individual to a brush carrier or support 63 (Fig. 1) carrying a pair of brushes 65 and 66 for each pair of code discs 13.

Each of the brush supports 63 has formed on one of its arms a horizontal projection 67 which lies in the path of its individual selectable bar 61, so that upon the operation of its bar 61, brush support 63 will be rotated in a clockwise direction about rod 64, as viewed in Fig. 1, against the action of its retractile spring 68, provided, however, the brush support 63 is at that instant free to move. As shown in Fig. 1, the brush support 63 has a horizontal extension 69 arranged with its end formed in a knife-like fashion to cooperate with a correspondingly shaped portion of a bail 70 which extends transversely of the code discs 13 and which is pivotally supported at its ends by brackets 71 and 72. Formed near the left-hand end of bail 70 is a projection 73 to which is attached a retractile spring 74 and a pivoted lever 76 which carries at its free end a cam roller 77 positioned to be operated cyclically by cam 24 which, as previously de-

scribed, is mounted on shaft 9. For each operation of cam 24 bail 70 will have its knife-shaped portion moved free of the correspondingly shaped projection 69 of the brush carrier 63 to release the brush carrier 63, whereupon it is restored to its normal position, or the position shown in Fig. 1, by the action of its individual retractile spring 68.

Common to all selectable members 61 is a bail 80 which is pivotally mounted on rod 64 and which has vertically projecting arms 45 and 46 to which cam rollers operatively positioned with respect to cams 25 and 26 are secured. Retractile springs 59 and 60 are secured to arms 45 and 46 of bail 80, respectively. For each rotation of cams 25 and 26 bail 80 will be rotated counterclockwise, as viewed in Fig. 1, against the tension of springs 59 and 60 to move the selectable bars 61 free of the permutation bars 31 and 35 to permit their operation, and subsequently will release the selectable bars 61 to permit one of such bars to be selected through the alignment of a set of notches in permutation bars 31-35.

When the permutation bars 31-35 are positioned in various combinations in response to the permuted energization of electromagnets 37-41, a selectable bar 61 will be rotated about rod 64 by its spring 62 to engage projection 67 of brush carrier 63, since at this instant bail 70 is free of extension 69 of its brush carrier 63. The brush support 63 individual to the operated selectable bar 61 will be moved against the action of its spring 68 to bring the brushes 65 and 66 into operative relation with respect to the pair of code discs 13 to which the operated brush support 63 is individual. Following the setting of the brush support 63, locking bail 70 is restored by its spring 74 to a position where it engages extension 69 of brush support 63 and holds such brush support in its set position. The selectable member 61 is thereupon free to be restored to its normal position out of cooperation with the permutation bars 31-35 through the action of bail 80, and thus the permutation bars may be reset to select either the same selectable bar 61 or another selectable bar 61 identified with a pair of code discs 13. With such an arrangement it is possible to initiate a selection during the interval the brushes 65 and 66 are in engagement with the code discs 13 for the transmission of signal impulses characteristic of their peripheral formation.

Following the selection of a selectable bar 61 and the operation of the brush support 63, a cam (not shown) mounted on shaft 9 is effective to operate through a system of levers, as fully disclosed in Patent No. 2,176,740, to E. E. Kleinschmidt of October 17, 1939, to restore each of the released permutation bars 31-35 to their normal position, or the position shown in Fig. 2, wherein the bars are held against the action of their individual springs by latches 44.

As previously described, a code disc 13 of each pair of code discs is connected to collector rings 15 and 16, respectively. Continuously in engagement with each of these rings are brushes 82 and 83, respectively (Fig. 2). These brushes are connected through electrical conductors to contacts 84 and 85. Cooperating with these contacts is a contactor 86 pivoted at one end and engaged at its other end with a rockable member 87. Secured to member 87 are two oppositely arranged bell crank levers 88 and 89 arranged to move member 87 to the right or left, depending

upon whether bell crank lever 88 or bell crank lever 89 is operated, to cause corresponding movement of contactor 86 to engage either contact 84 or contact 85.

Operation of bell crank levers 88 and 89 is achieved through selector bars individual thereto. As shown in Fig. 2, selectable bar 90 is individual to bell crank lever 88 while selectable bar 91 is individual to bell crank lever 89. Upon the selection and operation of either of the selectable bars 90 and 91 the bell crank lever 88 or 89 individual thereto will be operated and corresponding movement of member 87 will be effected. The selection and operation of the selectable bars 90 and 91, which are identified with "figures" and "letters" or shift and unshift signal combinations, respectively, are selected and operated through the setting of the permutation bars 31-35 in response to the energization of the electromagnets 37-41 for the signal combinations identified with figures and letters, respectively; that is, when a transverse row of perforations in tape 48 representing "figures" shift is sensed by mechanism 43, the contact members 54 will be operated to cause the energization of certain of the electromagnets 37-49 to set permutation bars 31-35 to align their notches to select and permit the operation of selectable bar 90. Under such conditions member 87 will be moved to the right through the rotation of bell crank lever 88 in a counterclockwise direction to cause engagement of contactor 86 with contact 85. Inasmuch as contactor 86 was previously in engagement with contact 84 and since contacts 84 and 85 are connected electrically to collector rings 15 and 16, respectively, the circuit will be changed from collector ring 15 to collector ring 16. Correspondingly, selectable bar 91 may be operated in response to a "letters" code combination in tape 48 to cause the member 87 to move contactor 86 from engagement with contact 85 into engagement with contact 84.

Inasmuch as a code disc of each pair of code discs 13 is connected either to collector ring 15 or collector ring 16 and since the circuit from the collector rings 15 and 16 is determined by the position of contactor 86, the effective circuit will depend upon the position of contactor 86 which, as shown in Fig. 2, is connected to a radio frequency transmitter 78 which may be of any well-known design.

Positioned near the entrance end of the tape sensing mechanism 43 is a mechanism commonly referred to as a taut tape switching mechanism which responds to the condition of the tape to exercise control functions. Such a mechanism, as exemplified in Fig. 2, embodies a bracket to which a lever 93 is pivotally mounted on a shoulder screw 94. A pin 95 is also mounted in this bracket and serves to limit the clockwise rotation of lever 93. One arm of lever 93 extends transversely of tape 48 and is arranged to be engaged by the tape if and when it becomes taut between the tape sensing mechanism and the perforator which functions to supply the perforated tape. The other arm of lever 93 extends vertically and is positioned such that its free end engages an insulated block secured to the free end of an electrical contact 96 which cooperates with an electrical contact 97 to control an electrical circuit which extends from battery, through said contacts 96-97, through a manually operated switch 99, and the winding of an electromagnet 103 to ground. Of course, with switch 99

open, the circuit for electromagnet 103 will not be completed; also, with contacts 96 and 97 open and with switch 99 closed, the circuit of electromagnet 103 will not be completed. However, with the lever 93 in the position shown in Fig. 2, which is its position when the tape 48 is looped as shown, contacts 96 and 97 will be closed, and with switch 99 closed electromagnet 103 will be energized.

As disclosed in Fig. 1, electromagnet 103 has its armature 104 pivotally mounted in a bracket 105 and held in its released position by a spring 106. Pivotally attached to armature 104 is a vertically extending lever 107 which is moved to the position shown in Fig. 1 by a spring 108 which has one end secured to arm 107 and the other end secured to a fixed spring post. Secured near the free end of arm 107 is a pin or worm follower 109 which, when electromagnet 103 is energized, engages the threads of worm 30 which as disclosed in Fig. 1 is formed in the left-hand end of shaft 9.

The upper end of arm 107, as disclosed in Fig. 1, is beveled and is arranged during its movement from right to left, as viewed in Fig. 1, when electromagnet 103 is energized, when follower 109 will be in engagement with the thread of worm 30 to operate successively contacts 112 and 113. The contacts 112 and 113, as will be described hereinafter, function to generate signal conditions which will cause operation of the radio transmitter 78 to transmit to the radio receiver 79 a signal effective to control the operating circuit of the driving motor of the receiving printer which is connected to the radio receiver network 79. Positioned beyond the left-hand end of shaft 9 are contacts 114 which are engaged by arm 107 in its extreme left-hand position in which position it will be moved by cooperation of follower 109 with the thread of worm 30.

As disclosed in Figs. 1 and 2, contacts 114 are normally open. These contacts, as disclosed in Fig. 2, control the energizing circuit of relay 118 in cooperation with contacts 116 which are identified as the pulsing contacts and which are operated cyclically by cam 27 mounted on shaft 9. For each rotation of cam 27 contacts 116 are closed to control, depending upon whether contacts 114 are closed, the energization of relay 118 and to close invariably the energizing circuit of electromagnet 50 of the tape sensing mechanism 43. Also cooperating with relay 118 and controlled by pulsing contacts 116 is a relay 117.

With electromagnet 103 de-energized, arm 107 will be rotated by the action of spring 108 to the position shown in Fig. 1, which operation occurs either upon the opening of switch 99 or the opening of contacts 96 and 97 in response to the tape 48 becoming taut and rotating lever 93 in a counterclockwise direction about its pivot 94. The de-energization of electromagnet 103 in this manner, permits the movement of lever 107, by its spring 108, away from the contact 114, thereby breaking the circuit for magnet 118. The locking coils 57 are not energized immediately upon the release of relay 118. The release of relay 118 prepares a path for a circuit through coils 57 so that upon the next closure of contacts 116, relay 117 will operate and complete the circuit beginning at grounded battery through the back contact of relay 118, through the contact of relay 117 just closed, through the right-hand winding of relay 117, and through the locking coils 57 to ground. Coils 57 remain locked in their energized condition due to the fact that the right-hand winding of relay 117 holds relay 117 energized.

Electromagnet 57, on becoming energized, will hold the bail 52 in its counterclockwise position to hold the sensing fingers 47 in their retracted position and preclude temporarily the sensing of the next transverse row of code perforations in tape 48. It is, of course, understood that during such period shaft 9 rotates continuously; however, no signals will be transmitted through the radio transmitter 78 because there are no brushes 65 and 66 in engagement with code discs 13.

Assume, for example, that switch 99 was closed and that tape 48 became taut to operate lever 93 and open contacts 96 and 97. Electromagnet 103 would thereupon become de-energized and arm 107 would be restored immediately by the action of spring 108 to its extreme right-hand position, or the position shown in Fig. 1. When the tape 48 becomes slack, or a loop is formed in that portion between the perforator and the tape sensing mechanism, lever 93 will be released and the tension of contact spring 86 will restore it to the position shown in Fig. 2. Accordingly, contacts 96 and 97 will be closed and an energizing circuit for electromagnet 103 will be completed extending from ground at battery, through contacts 96 and 97, closed contacts of switch 99, and the winding of electromagnet 103 to ground. Armature 104 of electromagnet 103 will be attracted against the tension of its spring 106, and arm 107 will be moved to a position where its follower 109 engages the thread in worm 30. Due to the fact that worm 30 rotates continuously, the follower with its arm 107 will be moved to the left in the direction of the arrow shown in Fig. 3. As arm 107 travels from its right-hand to its left-hand position, contacts 112 and 113 will be closed successively to generate in radio transmitter 78 two impulses in succession for transmitting signals corresponding thereto to the radio receiver 79 for effecting control of the receiving printer, as will be described hereinafter.

Follower 109 continues in engagement with the thread of worm 30 until it reaches the end thereof when it falls free of the worm, whereupon it closes contacts 114. Upon the closure of contacts 114 an energizing circuit for relay 118 is conditioned. Upon the next closure of pulsing contacts 116 through cam 27 the energizing circuit of relay 118 is completed, whereupon the energizing circuit for electromagnet 57 and relay 117 is opened. Electromagnet 57 and relay 117 thereupon are de-energized. Upon the opening of contact 116 electromagnet 50 will become de-energized and the tape sensing fingers 47 will be moved to a position to sense the then aligned transverse row of perforations in tape 48 and effect, through contacts 54, the transmission of a corresponding signal to electromagnets 31-41 to set correspondingly the permutation bars 31-35. Through the setting of the permutation bars 31-35 a selectable bar 61 will be selected and a brush support 63 will be operated to effect transmission through the cooperation of brushes 65 and 66 with discs 13 to transmit a group of signals determined by the peripheral contour of the selected disc of the pair of discs 13. The operation will be continued through the successive permuted setting of the permutation bars 31-35. For each rotation of shaft 9, cam 27 will close contacts 116 and will establish an energizing circuit for relay 117. However, since contacts 114 are closed, relay 118 will be energized simultaneously with relay 117. The circuit to locking magnets 57 is not closed because relays 117 and 118 are op-

erated simultaneously each time that contacts 96 are closed. Therefore, each time the contacts of relay 117 close, the contacts of relay 118 open and a circuit cannot be completed through both of these contacts to energize locking magnet 57. Such operation continues until switch 99 or contacts 96 and 97 are opened.

Upon the opening of contacts 96 and 97 in response to a taut tape condition through the operation of lever 93, the energizing circuit for electromagnet 103 will be opened, and its armature 104 will be moved to its retracted position by spring 106, wherein the follower 109 will be free of the worm 30. By the action of spring 108 arm 107 and its follower 109 will be moved from left to right, as indicated by the lower arrow in Fig. 3. Arm 107 remains in this position until electromagnet 103 is again energized in response to the closure of contacts 96 and 97. When these contacts are closed, electromagnet 103 is re-energized and arm 107 engages worm 30 and is moved from its right-hand to its left-hand position for closing in succession contacts 112, 113, and 114 for achieving the functions previously described.

As disclosed in Fig. 2, the radio receiving network 79, which may be of a design and construction to receive the signals generated through the operation of the radio frequency transmitter 18, functions to amplify, shape, and deliver signals of proper amplitude and shape to the printing telegraph receiver which is shown diagrammatically in Fig. 2 by the rectangle 81; that is, the signals delivered by the output circuit of the radio receiving network 79 are of such amplitude and shape as to operate efficiently the receiving printer indicated diagrammatically by the reference numeral 81.

The receiving printer which is electrically connected to the radio receiving network 79 involves a polarized relay 100 which, through its armature engaging contacts 122 and 123 (Fig. 4), serves to control the selector electromagnets of the receiving printer. The selector, as disclosed in Fig. 4, comprises an electromagnetic unit 124, consisting of a permanent magnet 128, a pair of magnetic coils 129 and 130, and a pivoted armature 131. Armature 131 is also provided with an extension 119 of insulating material, such as Bakelite. Also carried on armature 131 is a support 120 to which a printing knife-edge or platen 125 is secured. Platen 125 cooperates with a fluted printing wheel 126 which is driven continuously by a motor 127. The printing knife-edge or platen 125 functions to cause the paper strip 132, together with its carbon paper, to be moved into cooperation with the fluted printing wheel 126 to effect printing in response to the selective operation of the selector means as evidenced by the energization of the electromagnetic coils 129 and 130. The motor 127 drives the fluted printing wheel 126 through a gear 134, secured to the shaft of the motor, and a gear 135, secured to shaft 136, which carries the fluted printing wheel 126. Also mounted on shaft 136 is a worm gear 138 which is meshed with a gear 139 mounted on one end of a shaft 140 which also carries a worm gear 141. Worm gear 141 is meshed with a pinion gear 142 secured to shaft 143 on which is mounted a worm 144. With the motor 127 rotating continuously, fluted printing wheel 126, shafts 140 and 143, and worm 144 also rotate continuously.

Cooperating with worm 144 is a follower pin 145 mounted in the free end of an arm 147 at-

tached to armature 148 of an electromagnet 149. A spring 150 has one end attached to arm 147 and its other end attached to a fixed spring post, not shown, and functions to retain arm 147 in its counterclockwise position, or the position opposite to that shown in Fig. 4. A spring 151 is attached to armature 148 and serves to restore the armature to its de-energized position upon de-energization of electromagnet 149. With regard to arm 147 it is significant to note that it is mounted on armature 148 in a manner which permits its reciprocation from its counterclockwise position to the position shown in Fig. 4, through cooperation of follower 145 with worm 144, to engage an insulated block on the lower end of a contact spring 152 which cooperates with a contact spring 153 to control the operating circuit of motor 127; that is, when spring contacts 152 and 153 are in engagement (when arm 147 assumes its counterclockwise position), the circuit for motor 127 is completed, whereupon fluted printing wheel 126 and shafts 140 and 143 will rotate continuously.

Positioned below armature 131 of the electromagnetic unit 124 and carried on extension 119 thereof is an electrical contact 155 which is connected to a grounded battery, and which cooperates with a contact 156 mounted on the underside of armature 131, as shown clearly in Fig. 4. Contact 156 is connected through a reactance coil 157 to the windings of electromagnet 149.

Normally, the armature of relay 100 is positioned to engage contact 122 and complete a circuit from battery, through winding 130 of the electromagnetic selecting unit 124, so that the armature 131 will be rotated about its pivot in a clockwise direction, whereupon contacts 155 and 156 will be in engagement to establish an energizing circuit for electromagnet 149. Through the energization of electromagnet 149, and the rotation of armature 148 in a clockwise direction, follower 145 mounted on arm 147 will be moved to the right through its cooperation with worm 144 and will travel to its right-hand position to engage the insulated block on spring 152 and separate contact springs 152 and 153 and thereby to open the operating circuit of driving motor 127. During the time the armature of relay 100 is in engagement with contact 122, the winding 130 of the electromagnetic unit 124 is energized and contacts 155 and 156 are maintained closed to complete, accordingly, the energizing circuit of electromagnet 149 to hold the follower 145 in engagement with the worm 144 and maintain contacts 152 and 153 opened to maintain the power disconnected from motor 127.

As previously described, when contacts 96 and 97 are closed, assuming that switch 99 is closed, electromagnet 103 is energized and follower 109 engages worm 30; whereupon arm 107 will be rotated about its pivot to engage successively contacts 112 and 113. Through the closure of contact 112 an impulse is impressed on the radio transmitter 78 which transmits a signal corresponding thereto to the radio receiving network 79. The action of this signal impulse on the radio receiving network 79 is such as to cause reversal of the armature of relay 100, whereupon its armature is moved from engagement with contact 122 into engagement with contact 123. Upon the engagement of armature of relay 100 with contact 123, an energizing circuit is completed from battery, through the winding 129 of the electromagnetic selecting unit 124, and the

armature of relay 100. Armature 131 of the electromagnetic selecting unit 124 is thus moved in a counterclockwise direction to separate contacts 155 and 156 and thereby to open the energizing circuit for electromagnet 149. Upon the deenergization of electromagnet 149, spring 151 moves its armature in a counterclockwise direction, as viewed in Fig. 4, and removes follower 145 of arm 147 free of worm 144 so that spring 150 restores arm 147 to its extreme left-hand position. Upon the movement of arm 147 to the left, contacts 152 and 153 close, and the operating circuit of driving motor 127 is completed. Fluted printing wheel 126 and shafts 140 and 143 will thereupon be rotated.

Contact 112 is closed by the action of arm 107 only momentarily to effect the transmission of a corresponding signal. To insure the energization of relay 100 to close contact 123 to start the motor 127, contact 113 is closed following the closure and opening of contact 112 to complete a circuit including the radio transmitter 78, which responds to transmit to the radio receiving network 79 an impulse of identical form as the impulse generated through the closure of contacts 112. By providing contacts 112 and 113 and their closure successively, signal impulses are transmitted to insure the starting of the driving motor 127. Arm 107 continues its engagement with worm 30 to the end thereof where it falls off of the worm and closes contacts 114. The closure of contacts 114 prepares an energizing circuit for relay 118 which will be completed upon the closure of pulsing contacts 116. Therefore, when contacts 116 close, relay 118 becomes energized, and its armature, leaving its back contact, opens the circuit to locking coils 57 immediately. However, relay 117 does not become de-energized until contacts 116 are opened.

Pulsing contacts 116 will cause the successive energization of electromagnet 50 of the tape sensing mechanism 43 to permit the sensing fingers 47 to sense successively the transverse rows of perforations in tape 48. Incidentally, however, relay 117 does not remain de-energized during the successive energization cycles of electromagnet 50. Each time that contacts 116 close to operate electromagnet 50, relay 117 is operated simultaneously; also, if contacts 114 are closed, relay 118 is also operated simultaneously. During character transmission, therefore, relays 117 and 118 are operated simultaneously with electromagnet 50 upon each closure of pulsing contacts 116, and since relays 117 and 118 operate together, a circuit for the locking coils 51 is not completed.

For each transverse row of perforations in tape 48 the permutation bars 31—35, through the electromagnets 37—41, will be set permutably to select a selectable bar 61 and effect, through the code discs 13, the transmission of signal impulses through the radio transmitter 78 which functions to impress corresponding signal impulses on the radio receiving network 79. These impulses control polarized relay 100 to control, through its contacts 122—123, the energization of electromagnets 129 and 130 and thus the movement of armature 131, to cause the platen 125 to be brought into and out of cooperation with the fluted printing wheel 126 to effect printing of the characters represented by the peripheral contour of the discs 13, said printing being effected on the paper strip 132 through the instrumentality of a carbon strip. It is, of course, understood that during this operation the circuit for motor 127 continues through contacts 152 and 153.

For each energization of electromagnet 130, which will occur in response to the engagement of the armature of relay 100 with contact 122, contacts 155 and 156 will be closed and electromagnet 149 will be energized. Accordingly, follower 145 will be moved into engagement with worm 144 and will start its travel from left to right, as viewed in Fig. 4. However, the energization of electromagnet 149 following the signals as impressed upon relay 100 is only momentary and not of sufficient duration to permit the travel of arm 147 to a position to engage the insulated block of spring 152 and to separate springs 152 and 153 to open the circuit of motor 127. Consequently, even though contact 122 may be closed in response to the signals transmitted through the rotation of discs 13 in cooperation with either brush 65 or brush 66, electromagnet 149 will not be energized for a period sufficient for arm 147 to move to a point for opening contacts 152 and 153; therefore, during normal signal operation contacts 152 and 153 remain closed. If switch 99 is open or contacts 96 and 97 are separated in response to taut tape, electromagnet 103 will be de-energized, contact 114 will be opened, and the signal applied to transmitter 78 will be such as to cause relay 100 to maintain its armature in contact with contact 122 for maintaining winding 130 of electromagnetic selecting unit 124 energized. Contacts 155 and 156 will remain closed, and electromagnet 149 will be energized, whereupon follower 145 engages worm 144; and if worm 144 rotates, arm 147 is moved to the right to a point in engagement with the insulated block on contact spring 152. Upon further movement of arm 147 contact springs 152 and 153 are separated and the operating circuit of motor 127 is held open. Although the motor stops, which results in stopping of shafts 140 and 143, electromagnet 149 remains energized so that the arm 147 is held in its extreme right-hand position to maintain contact springs 152 and 153 open. In response to the first impulse effective through the closure of contacts 112, relay 100 disengages contact 122 and engages contact 123 to effect the starting condition of magnet 149 as previously described. Such condition prevails until electromagnet 103 at the transmitting station becomes de-energized in accordance with the sequence of operation described above.

Referring now to Fig. 5 wherein a modified form of the transmitter with its circuit connections is shown, it is pointed out that like the transmitter shown in Fig. 2 the transmitter shown in Fig. 5 comprises code bars 160, 161, 162, 163, and 164 under the control of electromagnets 165, 166, 167, 168, and 169. Electromagnets 165—169 are controlled by contacts 170 mounted on sensing levers 171 which serve to sense transverse rows of code perforations in a previously perforated tape 172 whereby the circuits for electromagnets 165—169 are operated permutably to set correspondingly permutation bars 160—164. Permutation bars 160—164 control the selection of selectable bars 173 in a manner identical to that described in connection with the structure shown in Figs. 1 and 2. Also, the selectable bars 173 control the circuits for code discs similar to code discs 13 which likewise are connected to common collector rings mounted on a continuously rotating shaft 175 in a manner similar to that described for the other species of invention. Also, the circuit connections to a radio frequency transmitter 178 are controlled through a contacting member 179.

The tape sensing mechanism differs, however, from the tape sensing mechanism disclosed in Fig. 2 in that in the form shown in Fig. 5 a single set of electromagnets 181 are employed for the control of the tape sensing elements of fingers 171. This electromagnet 181 has its circuit controlled by contacts 182 operated cyclically by a cam 183 mounted on shaft 175. A tape operated lever 184 cooperates with tape 172 to control the opening and closure of contacts 185 and 186. There is also included in circuit with contacts 185 and 186 a manually operated switch 187.

Like in the form disclosed in Figs. 1 and 2, the modification shown in Fig. 5 includes a worm 188 which is part of shaft 175 and which is adapted to be engaged by a follower pin mounted on lever 189 which is under the control of an electromagnet 190 which is energized upon the closure of switch 187 and contacts 185 and 186 to bring the follower carried by arm 189 into engagement with worm 188.

Arm 189 in its travel from right to left, as viewed in Fig. 5, closes contacts 191 and 192 in succession for transmitting through cooperation with radio transmitter 178 impulses to the radio receiving network 193 of a character to operate the printing telegraph receiver 194 in the manner fully described in connection with the operation of the structure shown in Figs. 1, 2, and 4. Upon the completion of the travel of arm 189 to its extreme left-hand position, contacts 195 are closed to complete an energizing circuit for electromagnet 196 which, through its armature 199 and a lever 198, controls the opening of contact springs 182 upon the rotation of cam 183.

It is observed that the upper spring of contact 182 is provided with an insulating portion which cooperates with lever 198, which in turn is adapted not only to cooperate with cam 183 but also to have latching engagement with armature 199 of electromagnet 196. With this arrangement the armature of magnet 196 under certain conditions of operation is latched behind (or to the left of) the latching projection on lever 198 so that the armature 199 cannot move toward the pole piece of magnet 196 (upon energization of said magnet) until cam 183 rotates lever 198 counterclockwise to raise the latching end thereof free of armature 199. Without this construction, it would be possible to withdraw the armature 199 of magnet 196 from under lever 198 at any point in the operating cycle and therefore open the circuit to the stepping solenoid 181 at a time in the operating cycle which might be improper. With the armature of magnet 196 obstructed by a projection on lever 198, however, the armature 199 cannot be removed from under the latching projection of lever 198 until this obstruction is removed by the proper position of cam 183, and this action provides the proper timing in the operating cycle. Some lost motion is provided between lever 198 and contacts 182, whereby contacts 182 will not be opened unless armature 199 is removed from blocking relation with lever 198.

The operation of the apparatus and the circuits disclosed in Fig. 5 will now be described. Assume that manual switch 187 has been closed and that contacts 185 and 186 are opened due to a tight tape condition of tape 172. When the tape becomes slack or attains a position such as that shown in Fig. 5, lever 184 will be in the position shown therein and contacts 185 and 186 will be closed to complete an energizing circuit for electromagnet 190 extending from grounded battery, through the closed switch contacts of switch 187,

contacts 185 and 186, conductor 197, and the winding of electromagnet 190 to ground. Electromagnet 190 in energizing moves arm 189 into engagement with worm 188, and since worm 188 rotates continuously, arm 189 will be moved from right to left, first to close contacts 191 and then contacts 192 to transmit in succession a starting impulse which will be effective to start the driving motor of the receiving printer in the receiving set 194 in a manner identical to that previously described. Arm 189 continues its movement from right to left until its follower falls off of the worm 188, when contacts 195 will be closed. The closure of contacts 195 completes an energizing circuit for electromagnet 196. Electromagnet 196 in energizing draws its armature 199 free of the lever 198 (if cam 183 is in the position shown in Fig. 5) and allows contacts 182 to open upon the further travel of cam 183. When contacts 182 are opened, electromagnet 181 of the tape sensing mechanism is de-energized and the sensing fingers 171 are permitted to move to a position to sense the then aligned transverse row of perforations in tape 172. Electromagnet 196 remains energized during the closure of contacts 195 so that for each rotation of cam 183 contacts 182 will be closed and opened to control correspondingly the energization of electromagnet 181 and thus the advancement and sensing of tape 172, the latter for the control of electromagnets 165-169 to set permutation bars 160-164 to determine the selection of a selectable bar 173 and the transmission of signal impulses in the manner fully described in connection with the apparatus disclosed in Figs. 1 and 2.

If, after the transmission of impulses is commenced, the tape 172 becomes taut, lever 184 will be moved in a counterclockwise direction about its pivotal support to open contacts 185 and 186, whereupon electromagnet 190 will be deenergized and arm 189 will be restored to its right-hand position, contacts 195 will be opened, and electromagnet 196 will be de-energized. The armature 199 of electromagnet 196, in response to its de-energization, assumes a position to block or prevent the opening of contacts 182 in response to the operation of cam 183; that is, with the armature 199 of electromagnet 196 in the position shown in Fig. 5, the lever 198 is not permitted to follow the rotation of cam 183 a distance sufficient to open contacts 182. Contacts 182, therefore, remain closed and continue the energization of electromagnet 181 of the tape sensing mechanism to preclude tape advancement and tape sensing for the setting of permutation bars 160-164 through the permitted energization of electromagnets 165-169.

In the arrangements disclosed in Figs. 2 and 5, the transmitting station and the receiving station are shown interconnected by a radio channel. It is, of course, understood that these stations may be interconnected by a line conductor.

The invention has been shown and described with regard to a particular form of apparatus. It is, however, obvious that the invention may be applied to other forms of apparatus without departing from the spirit and scope of the present invention.

What is claimed is:

1. In a telegraph system, a transmitter, a receiver having a normally inert driving motor, means in said receiver responsive to control impulses directly transmitted by said transmitter to control said motor, a signal channel connecting said transmitter and receiver, means in said trans-

mitter responsive to a starting condition to apply said control impulses to said channel, means at said receiver responsive to said control impulses for starting said motor, and timing means at said transmitter effective following the transmission of said control impulses to cause said transmitter automatically to transmit character signals over said channel.

2. In a telegraph system, a transmitter having record strip reading means, a receiver, having a normally inert driving motor, responsive to signals transmitted by said transmitter, a signal channel connecting said transmitter and receiver, timing means at said transmitter responsive to a starting condition to apply motor control impulses to said channel, means at said receiver responsive to said control impulses for starting said motor, means at said transmitter effective following the transmission of said control impulses to cause said transmitter automatically to transmit character signals, and means responsive to the tension of said record strip for discontinuing signal transmission from said transmitter.

3. In a telegraph system, a transmitter, a receiver having a motor, a signal channel connecting said transmitter and receiver, means for rendering said transmitter effective to transmit signal impulses over said channel for the supervisory control of said receiver motor, said means including timing means responsive to an electrical condition, and means controlled by said timing means and effective automatically after a predetermined period for causing said transmitter automatically to transmit receiver operating signals.

4. In a telegraph system, a transmitter, a receiver having a motor, a signal channel connecting said transmitter and receiver, means for rendering said transmitter effective to transmit signal impulses over said channel for the supervisory control of said receiver motor, said means including a magnet responsive to an electrical condition, means controlled by said magnet and operative through a predetermined cycle, and means operated by said magnet controlled means for causing said transmitter automatically to transmit receiver operating signals.

5. In a telegraph system, a transmitter, a receiver having a motor, a signal channel connecting said transmitter and receiver, means for rendering said transmitter effective to transmit signal impulses over said channel for the supervisory control of said receiver motor, said means including a magnet responsive to a local electrical condition, a continuously rotating worm, an arm movable by said worm, the cooperation of said arm with said worm being controlled by said magnet, and means operated by said arm when it attains a predetermined position for rendering the transmitter effective to transmit receiver operating signals.

6. In a telegraph system, a transmitter having a record strip reading means, a receiver having a motor, a signal channel connecting said transmitter and receiver, means comprising a plurality of pulsing contacts for rendering said transmitter effective to transmit control impulses over said channel for the supervisory control of said receiver motor, said means including means responsive to the condition of the record strip, and means controlled by said last-mentioned means for rendering said record strip reading means effective automatically to transmit receiver operating signals over said channel.

7. In a telegraph system, a transmitter having a record strip reading means, a receiver having a

motor, a signal channel connecting said transmitter and receiver, means comprising a plurality of pulsing contacts for rendering said transmitter effective to transmit control impulses over said channel for the supervisory control of said receiver motor, said means including means responsive to the condition of the record strip, and means controlled by said last-mentioned means for rendering said record strip reading means effective to transmit character signal impulses over said channel.

8. In a telegraph system, a transmitter having a record strip reading means, an electromagnet in said record strip reading means for precluding operation of said record strip reading means, a receiver having a motor, a signal channel connecting said transmitter and receiver, means for rendering said transmitter effective to transmit signal impulses over said channel for the supervisory control of said receiver motor, said means including means responsive to the condition of the record strip, and means controlled by said last-mentioned means for effecting the de-energization of the electromagnet in said record strip reading means for rendering, through said record strip reading means, said transmitter effective to transmit receiver operating signals over said channel.

9. In a telegraph system, a transmitter having a record strip reading means, a receiver having a motor, a signal channel connecting said transmitter and receiver, means for rendering said transmitter effective to transmit signal impulses over said channel for the supervisory control of said receiver motor, said means including means responsive to the condition of the record strip, pulsing means operated cyclically for controlling the step-by-step advancement of said strip, and timing means controlled by the means responsive to the condition of said record strip for rendering said pulsing means effective whereby said transmitter is operated to transmit receiver operating signalling impulses over said channel.

10. In a telegraph system, a transmitter having record strip reading means, a receiver having a motor, a signal channel connecting said transmitter and receiver, means for rendering said transmitter effective to transmit signal impulses over said channel for the supervisory control of said receiver motor, said means including a magnet responsive in accordance with the condition of the record strip, a continuously rotating worm, an arm moved by said worm, the cooperation of said arm with said worm being controlled by said magnet, pulsing means for controlling the step-by-step advancement of the record strip, and means operated by said arm when it attains a predetermined position for rendering said pulsing means effective to transmit receiver operating signals over said signal channel to said receiver.

11. In a telegraph system, a transmitter, a receiver, having a normally inert driving motor, responsive to signals transmitted by said transmitter, a signal channel connecting said transmitter and receiver, screw and follower means in said transmitter responsive to a starting condition to apply during the travel of said follower along said screw a starting impulse to said channel, means at said receiver responsive to said starting impulse for starting said motor, and means at said transmitter effective at the end of said travel to cause said transmitter automatically to transmit character signals.

12. In a telegraph system, a transmitter, a receiver, having a normally inert driving motor,

responsive to signals transmitted by said transmitter, a signal channel connecting said transmitter and receiver, timing means in said transmitter responsive to a starting condition to apply during a predetermined period of actuation of said timing means a starting impulse to said channel, means at said receiver responsive to said starting impulse for starting said motor, and means at said transmitter effective at the end of said period of actuation to cause said transmitter automatically to transmit character signals.

13. In a telegraph system, a transmitter, a receiver having a normally inert driving motor, control means for said motor responsive to signals transmitted by said transmitter, a signal channel connecting said transmitter and receiver, timing means in said transmitter responsive to a starting condition to apply during a predetermined period of actuation of said timing means a starting impulse to said channel for operating said control means to start said motor, and means at said transmitter effective at the end of said period of actuation to cause said transmitter automatically to transmit character signals.

14. In a telegraph system, a transmitter, a receiving printer having a normally inert driving motor, control means for said motor, printing means in said printer responsive to signals transmitted by said transmitter, contact means associated with said printing means for controlling the operation of said motor control means, a signal channel connecting said transmitter and receiving printer, timing means in said transmitter responsive to a starting condition to apply during a predetermined period of actuation of said timing means a starting impulse to said channel for operating said printing means to effect, through said contact means, the operation of said motor control means to start said motor, and means at said transmitter effective at the end of said period of actuation to cause said transmitter automatically to transmit character signals.

15. In a telegraph system, a transmitter, a receiver having a normally inert driving motor, control means for said motor, signal controlled printing means in said receiver, circuit controlling means for said motor control means associated with said printing means, signal responsive means in said receiver effective under certain conditions of operation of said transmitter to condition said printing means to render said motor control means operable to stop said motor, said signal responsive means effective under other conditions of operation of said transmitter to condition said printing means to render said motor control means effective to start said motor, and means in said transmitter effective under further conditions of operation to cause said transmitter automatically to transmit character signals, following the initiation of said motor into operation.

16. In a printing telegraph system, a transmitter, a receiver comprising a normally inert driving motor, a rotatable printing element driven by said motor, a platen co-operable with said element to effect printing, a rockable arm for supporting said platen, a polarized electromagnet for rocking said arm, control means for said motor, and circuit controlling means for said motor control means associated with said rockable arm, and means responsive to predetermined marking and spacing impulse conditions transmitted by said transmitter for controlling, through said electromagnet, the effectiveness of

said circuit controlling means in accordance with the nature of the impulse.

17. In a printing telegraph system, a transmitter, a receiver comprising a normally inert driving motor, a rotatable printing element driven by said motor, an instrumentality co-operable with said element to effect printing, and control means for said motor including a member carried by said instrumentality, and means responsive to predetermined signaling conditions transmitted by said transmitter for controlling, through said member, said motor control means.

18. In a printing telegraph system, a transmitter, a receiver comprising a normally inert driving motor, control means for said motor, a rotatable printing element driven by said motor, and an instrumentality co-operable with said element to effect printing, said instrumentality carrying circuit controlling means for said motor control means, and means responsive to predetermined signaling conditions transmitted by said transmitter for determining, through said instrumentality, the effectiveness of said circuit controlling means to govern said motor control means.

19. In a printing telegraph system, a transmitter, a receiver having a normally inert driving motor, control means for said motor, signal controlled printing means in said receiver, circuit controlling means for said motor control means associated with said printing means, and signal responsive means in said receiver effective under certain conditions of operation of said transmitter to condition said printing means to render said motor control means operable to stop said motor, said signal responsive means effective under other conditions of operation of said transmitter to condition said printing means to render said motor control means effective to start said motor.

20. In a printing telegraph system, a transmitter, a receiver comprising a normally inert driving motor, a rotatable printing element driven by said motor, a platen, a rocker arm for supporting said platen, polarized means for rocking said arm in accordance with received signals, control means for said motor, circuit controlling means for said motor control means associated with said rocker arm, and signal responsive means in said receiver effective under certain conditions of operation of said transmitter to condition said printing means to render said motor control means operable to stop said motor, said signal responsive means effective under other conditions of operation of said transmitter to condition said rocker arm to render said motor control means effective to start said motor.

21. In a telegraph system, a transmitter having a record strip reading means, a cam controlled means in said transmitter for precluding operation of said record strip reading means, a receiver having a motor, a signal channel connecting said transmitter and receiver, means for rendering said transmitter effective to transmit signal impulses over said channel for the supervisory control of said receiver motor, said means including means responsive to the condition of the record strip, and means controlled by said last-mentioned means to establish a condition for causing, through said record reading means, said transmitter automatically to transmit receiver operating signals over said channel, following the initiation of said motor into operation.

22. In a telegraph system, a transmitter having

a record strip reading means, a cyclically actuated cam means in said transmitter for operating said record strip reading means, control instrumentalities cooperable with said cam means for precluding operation of said record strip reading means, a receiver having a motor, a signal channel connecting said transmitter and receiver, means for rendering said transmitter effective to transmit signal impulses over said channel for the supervisory control of said receiver motor, said means including means responsive to the condition of the record strip, and means controlled by said last-mentioned means to establish, through said control instrumentalities, a condition for rendering said record strip reading means effective automatically to operate said transmitter to transmit receiver operating signals over said channel, following the initiation of said motor into operation.

23. In a telegraph system, a transmitter having a record strip reading means, means in said transmitter for precluding operation of said record strip reading means, a receiver having a motor, a signal channel connecting said transmitter and receiver, means for rendering said transmitter effective to transmit signal impulses over said channel for the supervisory control of said receiver motor, said means including means responsive to the condition of the record strip, and means controlled by said last-mentioned means to establish a condition for causing, through said record reading means, said transmitter automatically to transmit receiver operating signals over said channel, following the initiation of said motor into operation.
